Primary Examiner — Thomas Johannes(57) **CLAIM**

The ornamental design for a package for a consumer product, as shown and described.

DESCRIPTION

FIG. 1 is a top isometric view of an ornamental design for a first embodiment of a package for a consumer product; FIG. 2 is a front elevational view of the package of FIG. 1; FIG. 3 is a top isometric view of an ornamental design for a second embodiment of a package for a consumer product; FIG. 4 is a front elevational view of the package of FIG. 3; FIG. 5 is a top isometric view of an ornamental design for a third embodiment of a package for a consumer product; FIG. 6 is a front elevational view of the package of FIG. 5; FIG. 7 is a top isometric view of an ornamental design for a fourth embodiment of a package for a consumer product; and, FIG. 8 is a front elevational view of the package of FIG. 7. The broken lines in the drawings depict environmental subject matter only and form no part of the claimed design.
